LUBRICATING SYSTEM

Albert C. Peterson, Chicago, Ill., assignor to Union
Special Machine Company, Chicago, Ill., a
corporation of Illinois

Application April 2, 1940, Serial No. 327,387

10 Claims. (Cl. 184—6)

This invention relates to lubricating systems, and has reference more particularly to lubricating systems in which the oil is constantly circulated.

The present invention constitutes an improvement upon a form of lubricating system featured in a copending patent application Serial No. 231,299 filed by Edwin J. Broucek on September 23, 1938. In the system of that application, oil is drawn from a reservoir into a bearing by the action of a pump means jointly formed by said bearing and the portion of a shaft rotating within it, and forced into a lengthwise dead end duct in the shaft for conduction to a plurality of rotary actuators on said shaft beyond the bearing. In this construction, the pump means operates to maintain the oil in the shaft duct under pressure so that an excess amount of it is continuously forced through the rotary actuators, with the result that the oil supply soon becomes depleted and that such excess oil is wasted.

One of the aims of my invention is to overcome the disadvantages above pointed out, which objective I realize in practice as hereinafter more fully disclosed, by providing for return of oil in excess of the amount sufficient for the proper lubrication of the shaft and the actuators thereon, to the reservoir by action of the pump means so that the oil is continuously circulated in the system without undue wastage.

A further aim of my invention is to secure, by simplification and improvement in a manner also fully set forth in detail hereinafter, a higher operative efficiency in the pumping means jointly formed by the shaft and its bearing.

As was the case with the lubricating system of the copending application, supra, the system of my invention is especially useful in connection with high speed sewing machines, although it is adaptable to other types of machines where constant bathing of moving parts with lubricating oil is desirable or essential for efficient performance.

Other objects and advantages of my invention will appear from the following detailed description of the attached drawings, wherein Fig. 1 is a view partly in elevation and partly in longitudinal section, of an overedge sewing machine conveniently embodying the present improvements.

Fig. 2 shows the upper portion of the machine in side elevation.

Fig. 3 is a detail sectional view taken as indicated by the angled arrows III—III in Fig. 2.

Fig. 4 is a fragmentary detail sectional view corresponding to Fig. 1 drawn to a larger scale.

Fig. 5 is a fragmentary detail sectional view taken as indicated by the arrows V—V in Fig. 4.

Fig. 6 is a fragmentary view in elevation showing part of the driving shaft of the machine.

Figs. 7 and 8 are detail views in side elevation of two different types of rotary actuators embodied in the machine.

The needle bar 10 of the sewing machine is inclined somewhat to the vertical and guided in an inset bearing sleeve 11 at the bottom 12 of a head 13 which is supported by a hollow standard 14 rising from the work support 15 and which overhangs said support. Set into the front and rear walls 16 and 17 of the standard 14, are bearings 18 and 19; and journaled in these bearings is a shaft 20 which extends longitudinally of the hollow of the standard and which is inclined downwardly somewhat relative to the horizontal from the front bearing to the rear bearing. Mounted on the shaft 20 within the standard between the bearings 18 and 19 are rotary actuators in the form of eccentric 22, 23, 24 and 25 whereof the straps 22a, 23a, 24a and 25a are connected, by rods 26, 27, 28 and 29, with various elements associated with complementary stitch forming mechanism and feeding mechanism (not illustrated) within the base 30 of the machine of which the work support 15 constitutes the top. The presser foot 31 of the machine is pivotally connected at 32 to the outer end of the horizontal arm 33 fulcrumed for up and down movement about a pivot 35 on the standard 14. A presser bar 36 suitably guided in the head 13 and subject to the action of a compression spring (not shown) bears at its lower end into a recess 37 in the top of the arm 33 to yieldingly urge the presser foot 31 downwardly. The head 13 has a removable box-like front cover 38 for protecting the parts by which the needle bar is reciprocated, these parts including a pitman 39 which, at its upper end, is pivotally connected to the top of said needle bar, and which, at its lower end, is connected to a balanced disk crank 40 on the front end of the shaft 20. At the rear of the machine, the shaft 20 extends to the exterior for attachment of a combined hand wheel and pulley 41. As shown, the belt 42 for the pulley extends down through a clearance opening 43 in a table 44, whereon the machine is supported, to power drive means (not illustrated) beneath said table.

For the purpose of automatically lubricating a sewing machine such as briefly described by

way of example, I have, in accordance with my invention, made provisions as follows:

Integrally formed with a cover member 45 which closes the hollow of the standard 14 at the top, is an oil reservoir 46 having a removable lid 47. A supply of lubricating oil is maintained in the reservoir 46 by a transparent oil cup 48 of the inverted constant level type screwed into one side wall of said reservoir, indicated at L in Fig. 1. Extending from the bottom of the reservoir 46 within the standard 14 is a gravity flow tube or duct 49 which connects with a vertical bore 50 in the partition 16 in line with a port 51 in the top of the bearing 18. In the plane of the port 51 is a groove 52 which extends part way around the shaft 20 within the confines of the bearing 18, and which, it will be noted, is of uniform width and depth throughout its length. At one end, the groove 52 communicates, by way of a radial port 53, with an axial duct 54 in the shaft 20. As shown in Fig. 1, the duct 54 is closed at its front end by a screw plug 55 which is accessible upon removal of the front cover 33 from the needle head 12, and extends rearward to a point beyond the center of the bearing 19. From the duct 54 oil is conducted, by way of radial ports 56 in the shaft 20, to circumferential grooves 57 internally of the eccentrics 22-25, and from said grooves by way of one or more connecting radial ports 58 as shown in Figs. 1, 7 and 8, to the bearing surfaces of said eccentrics, the last mentioned ports containing flow-restricting filter packing as conventionally indicated in Figs. 1 and 4. Within the confines of the bearing 19, the shaft 20 has a radial port 59 which communicates with a circumferential groove 60 internally of said bearing. Leading upward in the bearing 19 from the groove 60 is a port 61 which registers with a vertical bore 62 in the rear wall 17 of the standard 14. At the region of its overlap upon the wall 17, the cover 45 is recessed as at 63 to form in conjunction with an interposed plate 64, a channel which communicates by way of a port 65 in said plate with the top of the bore in said wall. Extending up from the channel 63 is a tube 66 which reaches up within the reservoir 46 and terminates in a goose neck discharge end above the oil level. Beneath the base 30 of the machine is a drip pan 67 which drains, through a central tube 68, into a removable oil collecting receptacle 69 below the table 44.

During each rotation of the shaft 20, which is in the direction of the arrow in Fig. 5, a quantity of oil gravitates from the reservoir by way of the connection 49, the duct 50 and the port 51 in the bearing 18, into the interrupted groove 52 in said shaft while the groove is in registry with said port. As the shaft 20 continues in its rotation, the charge of oil thus is trapped, due to its inertia, cannot follow the rapid movement of the shaft, and part of it is accordingly forced from the groove 52 through the port 53 into the shaft duct 54. By successive injections of such charges, the oil in the shaft duct 54, aided by gravitation due to the downward slope of the shaft, is constantly advanced leftward in Fig. 1, and the quantity over and above that required to keep the packing in the eccentrics moist, is forced upward through the port 61 in the bearing 19, the duct 60, port 65, passage 63 and tube 66, and finally discharged from the top end of the latter into the reservoir 46. In this way, the oil is constantly maintained in circulation in the system and lasts al-

most indefinitely since but an infinitesimal amount can escape past the bearing surfaces of the eccentrics, such escape oil finding its way down through the machine base 30 into the drip pan 67. Accordingly, oil replenishment is necessary only at very protracted periods, while wastage is reduced to an absolute minimum.

The sewing machine herein shown and described is to be regarded as exemplary of other types of machines with which the circulating lubricating system of my invention may be readily incorporated by modifications within the scope of the appended claims for attainment of advantages in all respects like those hereinbefore particularly pointed out.

Having thus described my invention, I claim:

1. A lubricating system for machines having a shaft, a bearing in which the shaft is journaled, and a rotary actuator on the shaft beyond the bearing, said system comprising an oil reservoir, a flow connection leading from the reservoir and entering the bearing through a port at right angles to the shaft, a lengthwise duct in the shaft leading from the region of the bearing to the rotary actuator, a return connection leading from the shaft duct beyond the rotary actuator to the reservoir, a pump means for circulating the oil in the system, including a groove which extends part way around the shaft within the bearing in the plane of the port, and a radial port at the trailing end of the groove as considered with reference to the direction of shaft rotation, which communicates into the shaft duct.

2. A lubricating system according to claim 1, in which the interrupted groove is of uniform depth and width throughout its length.

3. A lubricating system for machines having a substantially horizontal shaft, a bearing in which the shaft is journaled, and a rotary actuator on the shaft beyond the bearing, said system comprising an oil reservoir at an elevation above the shaft, a gravity flow connection leading from the bottom of the reservoir to a port extending down through the bearing to the shaft, a lengthwise duct in the shaft, a port leading from the bearing to the rotary actuator on the shaft, a return connection extending upward from the shaft duct beyond the rotary actuator and discharging into the reservoir from above, and pump means jointly formed by the shaft and the bearing within the confines of the latter for circulating the oil in the system.

4. A lubricating system according to claim 3, in which the pump means includes a groove which extends part way around the shaft in the plane of the port in the bearing, and a port at the trailing end of the groove, as considered with reference to the direction of shaft rotation, communicating into the shaft duct.

5. A lubricating system for machines having a substantially horizontal shaft, a pair of spaced bearings in which the shaft is journaled, and a rotary actuator on the shaft intermediate the bearings, said system comprising an oil reservoir at an elevation above the shaft, a gravity flow connection leading from the bottom of the reservoir to a port extending down through one of the bearings to the shaft, a return connection leading up from the shaft from within the other bearing and discharging into the reservoir from above, a lengthwise duct extending through the shaft between the two bearings, a radial port in the shaft within said other bearing by way of which the shaft duct communicates with the re-

turn connection, another port in the shaft leading from the duct to the bearing surface of the rotary actuator, and pump means jointly formed by the shaft and the first mentioned bearing within the confines of the latter for circulating the oil in the system.

6. A lubricating system according to claim 5, in which the pump means includes an interrupted circumferential groove in the surface of the shaft in the plane of the port in the first mentioned bearing, and a radial port at the trailing end of the groove as considered with reference to the direction of shaft rotation, communicating into the shaft duct.

7. The combination with a sewing machine having a work support with a hollow standard rising therefrom, bearings respectively in the front and rear wall of the standard, a substantially horizontal shaft extending longitudinally through the standard and journalled in the bearings, a plurality of rotary actuators on the shaft within the standard, and a top cover for the standard; of a lubricating system comprising an oil reservoir on the cover of the machine standard, a gravity flow connection leading from the bottom of the reservoir within the standard to a port extending down into the shaft bearing in the front wall of the standard, a return connection leading from a port in the top of the bearing in the rear wall and discharging into the reservoir from above, a duct extending between the bearings within the shaft, ports leading from the shaft duct to the bearing surfaces of the respective rotary actuators, and pump means jointly formed by the shaft and the bearing in one of the walls of the standard for circulating the oil in the system.

8. The combination according to claim 7, in which the pump means includes a groove which extends part way around the shaft in the plane of the port in the front wall bearing, and a port at the trailing end of the groove as considered with reference to the direction of shaft rotation, communicating into the shaft duct.

9. A lubricating system for machines having a substantially horizontal hollow shaft journalled in spaced bearings, said system comprising a lubricant reservoir above the shaft, a duct leading downwardly from the reservoir to one of the bearings, intermittent pump means jointly provided by such bearing and the shaft, whereby, during each rotation of the shaft, a definite quantity of lubricant is trapped from the reservoir and forced into the shaft hollow, and a duct leading upward from another of the bearings direct to the reservoir for returning to the latter excess oil forced into the shaft as aforesaid.

10. A lubricating system for machines having a substantially horizontal hollow shaft journalled in spaced bearings, and an actuator on said shaft for operating mechanism, said system comprising a lubricant reservoir above the shaft, a duct leading downwardly from the reservoir to one of the bearings, intermittent pump means jointly provided by such bearing and the shaft, whereby, during each rotation of the shaft, a definite quantity of lubricant is trapped from the reservoir and forced into the shaft hollow, means for conducting lubricant from the hollow of the shaft to said actuator, and a duct leading upward from another of the bearings direct to the reservoir for returning to the latter excess oil forced into the shaft as aforesaid.

ALBERT C. PETERSON.
